UNITED STATES PATENT OFFICE.

WILLIAM MORGAN, OF PITTSBURG, PENNSYLVANIA, ASSIGNOR TO THE PITTSBURGH MOTOR VEHICLE COMPANY, OF SAME PLACE.

DESIGN FOR A MOTOR-VEHICLE FRAME.

SPECIFICATION forming part of Design No. 29,544, dated October 25, 1898.

Application filed June 21, 1898. Serial No. 684,108. Term of patent 7 years.

To all whom it may concern:

Be it known that I, WILLIAM MORGAN, a citizen of the United States, residing at Pittsburg, in the county of Allegheny and State of Pennsylvania, have invented a new and useful Design for Motor-Vehicle Frames, of which the following is a specification, reference being had to the accompanying drawings, forming part thereof, in which—

Figure 1 is a side view of a motor-vehicle frame embodying my design. Fig. 2 is a top or plan view thereof, and Fig. 3 is a rear end view of the same.

The leading or characteristic features of my design comprise the rear portion thereof, which consists of a horizontal axle-tube having horizontal supporting-tubes connected thereto on each side of fittings. These horizontal supporting-tubes extend inwardly at an angle and are connected by fittings to a horizontal main-frame tube.

As illustrated in the drawings, A represents the horizontal axle-tube, having the fittings B secured around the same and provided

with the tubular extension A' beyond one of the fittings B.

C represents the supporting-tubes, which are connected or secured to the fittings B and extend inwardly and are connected or secured to the fittings D on the ends of the horizontal main-frame tube E.

The main frame F of the motor-vehicle is connected to the horizontal main-frame tube E at G.

Having described my invention, what I claim as new, and desire to secure by Letters Patent, is—

The design for a motor-vehicle frame substantially as herein shown and described.

In testimony whereof I have hereunto set my hand, at Pittsburg, in the county of Allegheny and State of Pennsylvania, this 20th day of June, A. D. 1898.

WILLIAM MORGAN.

In presence of—

J. N. COOKE,
JAMES K. CLARKE.
